UNITED STATES PATENT OFFICE.

LAWRENCE B. SPERRY, OF MASSAPEQUA, NEW YORK; THE BANK OF AMERICA, OF NEW YORK, N. Y., AND WINIFRED ALLEN SPERRY, OF HEMPSTEAD, NEW YORK, EXECUTORS OF SAID LAWRENCE B. SPERRY, DECEASED, ASSIGNORS TO WINIFRED ALLEN SPERRY.

FLYING BOAT.

Application filed July 26, 1918. Serial No. 246,832.

This invention relates to hydroaerial craft, commonly known as flying boats, and has for its object the increased safety of such craft when resting upon the water, and especially when the engine is crippled and the weather is rough.

Referring to the drawings wherein I have shown what I now consider the preferred form of my invention:

10 Fig. 1 is a side elevation of a flying boat embodying my invention.

Fig. 2 is a sectional detail of the fuel tank, showing means for emptying the fuel therefrom when desirable to lighten the craft.

15 Fig. 3 is a section of the lower portion of the boat taken approximately on line 3—3, Fig. 1, showing the method of strengthening the boat.

Fig. 4 is a detail showing a pump for forcing air into the fuel tank.

20 Fig. 4^a is a detail of the pump of Fig. 4.

Fig. 5 is a section taken on line 5—5, Fig. 1, showing means for retarding the movement of the rear end of the craft through 25 the water.

I have found that when a flying boat is floating freely upon the water during an appreciable gale, it will not only drift with the wind, but will tend to travel faster than 30 the waves, especially when moving forward or backward. It will be readily seen that if the craft moves backward faster than the waves, when the boat rolls and the ends of the wings or planes touch the water, a considerable downward pull will take place as 35 a result of the angle of the planes with respect to the water, and a tremendous strain will be exerted upon the craft. If, on the other hand, the boat is moving forward, and 40 the planes dip into the water, they will ride upwardly and skip along the surface. Thus, not only will strains tending to upset the craft be avoided, but forces tending to keep the craft steady and on even keel will be exerted.

In order, therefore, to cause the craft to be driven forward before the wind, I may provide means such as a flat board 1 or the like, hingedly secured as at 2 to the bottom

of the rear end of the boat 3. Normally the 50 board or drag 1 may be folded against the bottom of the boat or into a recess indicated by dotted lines 4 in the boat. A spring 5 or other suitable means may be provided for holding the drag in its closed position. A 55 wire 6 may be provided with one end fastened to the drag as shown at 7, and extending to within reach of the pilot. This wire is shown as fastened to a lever 8 pivoted at 9 to the boat. The parts are shown in 60 operative positions, but when lever 8 is released spring 5 will return said parts to their normal and inoperative positions.

When the craft is resting on the water, the pilot will actuate lever 8 so as to pull the 65 drag 1 down, and the drag will so retard the passage of the rear end of the craft through the water as to always permit the forward end to proceed first.

In order to keep the tail planes 10 clear of 70 the water, I may mount them high above the rear end of the boat as shown, by mounting them on a raised frame work 11 provided for this purpose.

An important feature of my invention is 75 the reduction of the weight of the craft by eliminating the metal fuel tanks. These tanks may be replaced by inserting partitions 12, 13, 14 and 15 in the hull of the boat; the compartments thus formed serving as 80 fuel tanks. The interior of these tanks may be coated with any suitable elastic varnish not subject to the action of gasoline. In this way it will be seen that the tops, sides and bottoms of the tanks will be obtained with- 85 out the use of additional material, being a portion of the hull of the boat.

I desire to provide means for ejecting the fuel from the tanks when the engine of the boat is crippled and cannot be used, in order 90 to further lighten the craft. For this purpose I have shown valves 16 in the bottom of the tanks. These valves may comprise a sleeve portion 17 having perforations 18 in the sides thereof, and the internal portion 95 19 having cooperating perforations 20, which perforations when brought into alignment will form an opening in the bottom of

the tank. A rod 21 attached to the portion 19 and to a bell crank lever 21' may serve as means for opening the valves. The bell crank levers 21' are in turn actuated by a rod 22 secured to the actuating lever 23. A wind actuated fan 24 is shown for normally pumping the fuel from the tanks through a tube 25 to the engine 26. This same fan may be used to pump air into the tanks to force the fuel out through the bottom.

For this purpose I have shown this fan as actuating a pump 27. The lower portion of this pump may be provided with a valve 28 shown here in open position. Thus it will be seen that as the fan rotates and the piston of the pump is operating no air will be forced through tube 29 into the tanks. But when it is desired to empty the tanks 20 the pilot will close valve 28 by turning knob 30 to screw valve rod 30' out through threaded bearing 28' so that the pump will now force the air through tube 29 into the fuel tanks. Small apertures 31 may be provided in the upper part of the intervening compartments 13 and 14 for allowing the air when pumped into one of the tanks to pass into the others.

The pump may be of the usual force type 30 with air inlet at 50, piston valve 51 and check valve 52, as shown in Fig. 4^A. Opening of valve 28 renders the pump ineffective either to pump fuel through pump 25 to the tank 26 or to empty the tanks. Closing 35 of valve 28 will cause pumping of fuel to tank 26 if the valves 18—19—20 are closed; but if the latter valves are open when valve 28 is closed, operation of the pumps will empty the tanks.

40 When short trips are being made the middle tank only need be used and valves 32 and 33 may be closed; but when making long trips all of the tanks will, of course, be brought into use, and valves 32 and 33 may 45 be opened to allow the fuel to flow into the middle compartment whence it is pumped up to the engine. The valves 32 and 33 may be actuated by rods 34 secured to bell crank levers 35, which are in turn 50 connected to actuating lever 37 by a rod 36.

In Fig. 3 I have shown means for strengthening the bottom of the hull. This means may comprise a pair of braces 38 and 39 secured at their inner ends 40' to the keel portion 40 of the boat and pressing against the sides of the boat at 41, being imbedded in the ribs 41'. These braces may be tied together by an inverted channel-shaped metal tie piece 42, the ends of this metal 60 piece being closed and the ends of braces 38 and 39 placed in the tie piece abutting against the closed ends thereof. Clips 43 may further secure the strengthening unit to ribs 41'. Thus it will be seen that when 65 the boat strikes the water these strengthen-

ing braces and tie piece will prevent the bottom of the boat being pressed upwardly, and will hold the boat rigidly in shape. In this connection it will be seen that partitions 12, 13, 14 and 15 will also act to 70 strengthen the structure of the boat.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to 80 use the various features and elements in the combination and relations described, some of these may be altered and others omitted without interfering with the more general results outlined, and the invention extends 85 to such use.

Having described my invention, what I claim and desire to secure by Letters Patent is:

1. A flying boat comprising a hull, rearwardly inclined aerial supporting surfaces attached to said hull, a vertical rudder for steering the same while in flight, and means attached to the rear part of said hull for causing said boat to turn into a position in 95 which it may be driven forwardly by the wind when floating on the water.

2. In a flying boat, a hull containing the aviator's seat and controls, aerial supporting surfaces, an engine, partitions in said 100 hull for forming certain of the walls of a fuel container, said hull forming the remaining walls of said container, means connected with said container for elevating the fuel to said engine, a valve adjacent the 105 bottom of said container, means for actuating said valve, and means for compressing air in said container for forcing the fuel out through said valve.

3. In combination with a flying boat having a hull, a rearwardly inclined aerial supporting surface and vertical rudder normally above the water-line, means comprising a drag member attached to said hull between the center of said boat and the latter 110 end thereof for causing said boat to turn in the water about a vertical axis in response to blowing of the wind to present an upwardly inclined surface in the direction of advance of the boat as it is propelled by the 115 wind, and means for rendering said drag member either operative or inoperative.

4. In a flying boat, an engine, a fuel tank below said engine, a pump for pumping fuel from said tank to said engine, and 125 means whereby said pump may be caused to pump air into said tank to assist in emptying the same.

5. In a flying boat, an engine, a fuel tank below said engine, a wind driven pump, and 130

means whereby said pump may be caused to pump air into said tank to assist in emptying the same.

6. In a flying boat, an engine, a fuel tank below said engine, a pump for pumping fuel from said tank to said engine, said tank having an emptying valve operable from the

driver's seat, and means whereby said pump may be caused to pump air into said tank to assist in emptying the same when said valve 10 is open.

In testimony whereof I have affixed my signature.

LAWRENCE B. SPERRY.
